UNITED STATES PATENT OFFICE.

JOSEPH F. MOODY, OF TULSA, OKLAHOMA.

ELEVATOR.

Application filed December 24, 1923. Serial No. 682,434.

To all whom it may concern:

Be it known that I, JOSEPH F. MOODY, a citizen of the United States, residing at Tulsa, in the county of Tulsa and State of Oklahoma, have invented new and useful Improvements in Elevators, of which the following is a specification.

This invention relates to elevators especially adapted for use in oil well operations.

10 An important object of this invention is to provide an elevator which may be conveniently attached to a sucker rod or the like or removed therefrom without endangering the operator.

15 A further object is to provide an elevator wherein the manually controlled knob for moving the rod confining dogs to inoperative position is arranged at the rear side of the elevator and forms a convenient gripping means whereby the elevator may be either attached to or removed from a sucker rod or the like.

20 A further object is to provide an elevator wherein rod confining dogs move to operative position immediately and automatically upon the entrance of the rod into the elevator so that the possibility of the elevator becoming accidentally disconnected from the rod is reduced to a minimum.

25 A further object is to provide an elevator of the character specified which is of highly simplified construction, durable in use and cheap to manufacture.

30 Other objects and advantages will be apparent during the course of the following description.

35 In the accompanying drawing forming a part of this application and in which like numerals are employed to designate like parts throughout the same,

40 Figure 1 is a fragmentary rear elevation of the elevator.

Figure 2 is a horizontal sectional view taken on line 2—2 of Figure 1.

45 Figure 3 is a vertical transverse sectional view taken on line 3—3 of Figure 2.

Fig. 4 is a perspective of a cam embodied in the invention.

50 In the drawing wherein for the purpose of illustration is shown a preferred embodiment of the invention the numeral 5 designates a body having its opposite sides provided with the usual trunnions 6 to which the U-shaped attaching member 7 is connected.

55 In carrying out the invention the body 5 is preferably in the nature of a

casting and is provided with upper and lower walls 8 and 9 respectively having slots 10 which extend out through the forward side of the body for the reception of a 60 sucker rod or the like.

Figure 2 plainly illustrates that the forward side of the body is curved inwardly at opposite sides of the openings 10 as indicated at 11 to guide the rod or the like into 65 the openings.

Also, the body is provided on opposite sides of the slots 10 with dogs 12 vertically pivoted as indicated at 13 to the forward portion of the body. It might be said that 70 the dogs 12 are located in recesses 14 at opposite sides of the opening in the body and the dogs are urged into the opening in the body by means of springs 16. The ends of the springs are seated in sockets 17 and 18 75 in the opposed sides of the dogs and the inner walls of the sockets 14. Of course when the dogs are moved to their advanced positions by the springs 16 the sucker rod is securely and positively held in the opening 80 in the body.

The dogs 12 may be moved outwardly or to their inoperative positions simultaneously by the turning of a cam 20 having oppositely directed lobes provided with rounded 85 edges to contact with the angularly directed rear end portions 22 of shanks 24 at the rear portions of the dogs. The lobe 20 may be manually turned by a knob 25 having a shank 26 connected to the intermediate portion of the cam by a pin or other suitable fastening device. The shank 26 is in turn rotatably connected to front and rear connecting posts 27 and 28. It will be seen that the fastening pin or key 30 holds the shank 90 26 against longitudinal movement and consequently the cam is held between the posts 27 and 28 and therefore constantly in an operative position.

Figure 2 illustrates that the forward side 100 of the connecting post 27 is concaved for contact with the sucker rod and consequently the post 27 forms the rear wall of the opening in the body. Also, the upper and lower walls 8 and 9 respectively are provided with transverse slots 34 to receive the end portions of the cam when the cam is in its inoperative position.

When it is desired to attach the elevator to a sucker rod or the like it is merely necessary for the operator to grasp the knob 25 110 and swing the elevator so that the sucker

rod is positioned in the opening 10. As the sucker rod enters the opening the dogs 12 are simultaneously swung outwardly and immediately upon the passage of the sucker rod the springs 16 will return the dogs to their operative positions. The accidental disconnection of the elevator from the sucker rod is positively prevented and the job of removing the sucker rod from the well may proceed safely. When the cups have been renewed or other necessary repair made the sucker rod may be returned to the well.

When it is desired to detach the elevator from the sucker rod it is merely necessary for the operator to grasp the knob 25 and turn the same so that the longitudinally curved edges of the cam will engage the angularly directed end portions of the shanks 24 and thereby move the dogs 12 to their inoperative positions. When the dogs 12 are moved to their inoperative positions in the sockets 14 the operator may pull rearwardly on the knob 25 to swing the elevator out of engagement with the box of the sucker rod. Attention is directed to the fact that it is not necessary for the operator to grasp any other part of the elevator when it is desired to remove the elevator from supporting engagement with sucker rod and thus the possibility of injury to the hands of the operator is reduced to a minimum.

In carrying out the invention it is not necessary to use the full width of the shanks 24 and the same may be scalloped or cut away at certain places and it is to be understood that certain minor changes in arrangement and construction of parts may be made as will remain within the spirit of the invention and the scope of what is claimed.

I claim:—

1. An elevator comprising a hollow body having upper and lower walls provided with slots, dogs pivoted at their forward ends within said body and having their rear portions formed with shanks, a cam positioned between said shanks, and a knob secured to said cam intermediate the ends thereof and forming a turning means for the cam and a gripping means for the elevator.

2. An elevator comprising a body having an opening and sockets on opposite sides of said opening, spring actuated dogs pivoted

in said sockets and adapted to extend into said opening, the rear portions of said dogs being provided with shanks, a cam having oppositely directed lobes adapted to engage said shanks, and a knob having a shank connected to the intermediate portion of said cam.

3. An elevator comprising a body having an opening and sockets on opposite sides of said opening, spring actuated dogs pivoted in said sockets and adapted to extend into said opening, the rear portions of said dogs being provided with shanks, a cam having oppositely directed lobes adapted to engage said shanks, and a knob having a shank connected to the intermediate portion of said cam, said body being provided with spaced front and rear posts between which said cam is arranged and the shank of said knob being rotatably connected to said posts.

4. An elevator comprising a body having upper and lower walls provided with slots, dogs pivoted between said upper and lower walls and having their rear portions formed with shanks, a cam having oppositely directed lobes adapted to engage said shanks to separate said dogs, said body being provided with strengthening and connecting posts joined at their ends to the upper and lower walls of the body and being arranged at opposite sides of said cam, a knob having a shank securely connected to said cam and being rotatably connected to said posts, the forward side of one of said posts being concave for contact by a cylindrical body.

5. An elevator comprising a body having an opening, a pair of dogs for closing said opening, a cam for moving said dogs to one position, a knob connected to said cam and adapted to be turned for actuating said cam, said knob constituting a means whereby the elevator may be grasped manually.

6. An elevator comprising a body having an opening, a pair of dogs for closing said opening, a cam for moving said dogs to one position, a knob connected to said cam and adapted to be turned for actuating said cam, said knob constituting a means whereby the elevator may be grasped manually, said knob being located at the side of said body opposite said opening.

In testimony whereof I affix my signature.

JOSEPH F. MOODY.
